UNITED STATES PATENT OFFICE.

GUY L. FREET, OF ALTOONA, PENNSYLVANIA.

COPY-HOLDING AND LINE-INDICATING DEVICE.

1,333,803.

Specification of Letters Patent. Patented Mar. 16, 1920.

Application filed February 12, 1918. Serial No. 216,777.

To all whom it may concern:

Be it known that I, GUY L. FREET, a citizen of the United States, residing at Altoona, in the county of Blair and State of Pennsylvania, have invented certain new and useful Improvements in Copy-Holding and Line-Indicating Devices, of which the following is a specification.

This invention relates to office appliances and has particular reference to copy holding machines wherein the line to be copied is indicated in a manner such that the operator may readily check his work as the same progresses.

15 The primary object of this invention is to provide a copy holding and line indicating means which is readily adapted to be used with statements having any length or line spacing.

20 Another object of this invention is to provide the copy holding means with a line spacing arrangement which is at all times positive in its action as well as easily operated, also inexpensive to construct and maintain.

25 With the above and many other objects in view which will be readily apparent as the nature of the invention is better understood, the same consists in the novel construction, combination and arrangement of parts as will be hereinafter fully pointed out, illustrated and claimed.

30 It will be quite readily understood by those skilled in the art to which this invention belongs; that the same is susceptible of some structural change or modification without departing from the spirit or scope of the invention, but a preferred and practical embodiment of the invention is shown in the 40 accompanying drawings in which—

Figure 1 shows a front elevational view of the present invention.

Fig. 2 shows an end elevation of the parts shown in Fig. 1, showing the drum and the 45 means used for rotating and locking the same.

Fig. 3 shows in detail the drum rotating and locking elements.

Fig. 4 shows the tension device employed 50 to return the operator's pedal to its initial position, after the operator has pressed the same down in order to rotate the cylinder.

Similar reference numerals refer to similar parts throughout the several figures of 55 the drawings.

In the construction of this device I have endeavored to eliminate all unnecessary elements, such as those that add to the initial cost and perform no independent and useful function and to this end the present invention consists essentially of a base board designated by the numeral 10, having attached thereto, two cylinder supporting brackets 11 and 12, each of which preferably take a triangular form with inwardly extending webs 13, which together with the integral face piece 14 gives the required rigidity as well as lightness to the construction.

At the apex of each triangular bracket the 70 faces 14 terminate in a circular base 15, which is perforated as shown at 16, for the purpose of forming a journal bearing for a rod 17 which carries a rotatable drum 18, around which the sheet to be copied from is 75 placed.

The drum 18 is preferably formed from sheet metal, of a suitable thickness, which is secured to annular rings 19, positioned at either end, as shown in Fig. 1 of the drawings.

The drum 18 is further provided with a sheet holding device 20, having the ends turned upwardly, inwardly, downwardly and outwardly such as to pass through a 85 suitably positioned opening 21 in the drum 18 and to enter an opening 22 in the web 23 where the same is fulcrumed, as shown in Fig. 2 of the drawings.

For the purpose of producing a suitable tension on the rod 20 there is provided a spring 24, the end 25 of which is secured to the drum 18 through suitable fastening means 26, while the free end 27 engages the inwardly extending portion of the rod 20, 95 and serves to keep the same drawn down on the surface of the drum.

For the purpose of rotating the drum 18 the required amount for single line spacing there is provided a drum rotating device, 100 consisting essentially of a lever 28, which is adapted to be fulcrumed at 29, and having provision at the end 30 for attaching thereto a vertical rod 31, the upper end 32 of which is adapted to be secured to a lever 33, 105 which is fulcrumed on the rod 17 as shown in Fig. 1 of the drawings.

The lever 33 carries a drum rotating element 34, which consists of a segment, fulcrumed at 35, and provided with a perfo- 110

rated lug 36 through which is adapted to pass a rod 37 fulcrumed at 38 which is provided with a tension spring 39 for keeping the surface 40 of the segment in contact with the surface 41 of the annular ring 19 as shown in Fig. 2 of the drawings. It is obvious from the construction shown in Fig. 2 that any downward movement of the lever 28 will cause an upward movement of the lever 33 and likewise a rotation of the drum 18.

For the purpose of keeping the drum from rotating counter clockwise there is provided a drum locking device which is shown more in detail in Fig. 3 and consists primarily of a spring actuated lever 42 having a notch 43 cut therein for the purpose of engaging the inside and outside periphery of the annular ring 19, tending in a very practical way to arrest any backward movement of the drum 18. From Fig. 3 it will be noticed that any clockwise motion of the drum is not prohibited by the locking element but at once any counter clockwise rotation is arrested. For the purpose of keeping the lever 42 in its proper position there is provided a spring 44, which is adapted to be coiled around the fulcrum post 45, having one free end resting upon a stationary lug 46 while the other rests against the lever 42 holding the same in position as shown in Fig. 3 of the drawings.

For the purpose of keeping the proper tension on the drum rotating device there is provided a tension adjusting mechanism as shown in Fig. 4 of the drawings which consists primarily of a helical spring 47, which is adapted to abut against the ledge 46 with one end while the other end is attached to the rod 31, which has associated therewith a movable bracket 48 and a wing nut 49 for clamping the bracket in any desired position.

The line indicating device designated in its entirety by the numeral 50 consists essentially of a plate 51 which is adapted to rest against the face of the drum 18. The plate 51 is fulcrumed on a rod 52, and co-acting therewith is a tension spring 53 which serves to keep the plate pressed

against the drum so as to firmly hold the paper in its proper place.

The rod 52 is fulcrumed on the brackets at either end at 54. Coöperating with a short horizontal section 55 of the road 52 there is a spring 56 adapted to be held in place by the screws 57, as shown in Fig. 2 of the drawings.

From the above description in connection with the drawings it is believed that the many advantages of the present invention will be readily apparent and what I claim and desire to be secured by Letters Patent is—

1. A copy holder including a frame and a drum having a traction flange rotatably supported therein, and means for intermittently rotating said drum consisting of a main operating lever pivoted coaxially with the drum, a feeding cam pivotally carried by the operating lever and having an offset eye, a rod loosely connected with the operating lever and slidably engaging said eye of the cam and carrying spring tensioning means therewith, an operator's lever pivotally mounted in the lower part of the frame, and a spring tensioned rod connecting the free end of the operator's lever and the main operating lever, said rod having a vertical guiding engagement with the frame.

2. A copy holding and line indicating device consisting of a frame, a copy holding drum rotatably journaled in the frame and presenting a flange at one end, a manually actuated device for engaging with said flange of the drum to advance the latter in one direction only, and means carried by the frame for preventing backward rotation of the drum consisting of a spring tensioned lever element having a notch in one edge thereof for engaging over the flange of the drum, the sides of said notch lying in a plane intersecting the circumference of the drum.

In testimony whereof I affix my signature.

GUY L. FREEET.
